UNITED STATES PATENT OFFICE.

PAUL J. SIMMEN, OF BERKELEY, CALIFORNIA.

AUTOMATIC RAILROAD BLOCK SYSTEM.

1,118,311.

Specification of Letter Patent. Patented Nov. 24, 1914.

Application filed June 3, 1907. Serial No. 377,062.

To all whom it may concern:

Be it known that I, PAUL J. SIMMEN, a citizen of the United States, residing at Berkeley, in the county of Alameda and 5 State of California, have invented new and useful Improvements in Automatic Railroad Block Systems, of which the following is a specification.

This invention relates to an automatic 10 block system for railroads, the object of the invention being to provide a system of this character which in general will be more certain and efficient in operation than the block systems heretofore employed; and which 15 furthermore will apprise the engine-driver or motorman whenever there is a defect in the cab circuit or in the line circuit.

A further object of this invention is to 20 provide a system of this character especially adapted for a single track railroad, in which there is a set of signals for ingoing trains and another set of signals for outgoing trains, all of which signals are normally at 25 clear, and which are so arranged that a train passing in either direction into a part of the track between two sidings will set at danger all the signals between said sidings for trains passing in the other direction.

In the accompanying drawings, Figure 1 30 is a diagrammatic view of one form of my improved block system. Fig. 2 is a dia- 35 grammatic view of the cab circuit of the system shown in Fig. 1. Fig. 3 is a longitudinal sectional view of one of the sole- 40 noids and Fig. 4 is a plan view of the same.

Referring to the drawings, 1 indicates a railroad track, adjacent to one side of which are a series of groups of contact rails 2, 3, 4, and 5. Whenever the engine arrives at one 45 of these contact rails, a circuit is closed in the cab, as hereinafter described. The first contact rail 2 of each group serves to notify the engine-driver to be prepared to stop before he passes the next contact rail 3, and, consequently, the distance between these rails 2 and 3 is arranged to be the maximum distance in which any train can be stopped as quickly as possible from its maximum speed. These rails 2 and 3 of each group 50 are connected by a wire 6, and may therefore for electrical purposes be considered as a continuous rail, although the signal is first given by the rail 2, and then repeated by the rail 3. These rails 2 and 3 might be 55 made in a single continuous contact rail, but this construction is avoided on account of expense.

In Fig. 1, the signal devices are shown in their normal condition and in this condition, a wire 7 leads from the rail 3 to a contact point 8 which is in contact with a contact changer 9 carried by the core 10 of solenoids 11, 12. Connected with said contact changer 9 is a flexible wire 13 which leads to a wire 14 and thence to ground at 15, said ground being in this case represented by one of the rails of the track. Therefore, if the contact at 8, 9, is closed, the arrival of the engine both at the rail 2 and at the rail 3, closes said circuit in the cab, and thereby 60 assures the engine-driver that the track ahead of him is clear. The train then proceeds until the engine arrives at the rail 4 of the same group, the effect of which is to close a circuit as follows: by a wire 17 65 through the front solenoid 11, of the adjacent pair of solenoids 11, 12, then by a wire 18 leading back over the line to the rear solenoid 12 of the pair of solenoids one block behind, and then by wire 14 to ground 70 at 15. The effect of this is to energize the front solenoid 11 of the pair at the front end of the block and the rear solenoid 12 at the rear end thereof, thereby attracting the 75 core at the front end of the block forward and retracting the core at the rear end of the block. Since this action takes place at each block station in turn, the core at each 80 station is left in the advanced position as the engine leaves said station, and when the 85 engine arrives at the next station in advance said core is returned to its normal condition in which the contacts 8 and 9 are closed. Thus, as the engine passes each block station, it separates the contacts 8 and 9 of the 90 station immediately behind, which if closed would actuate the clear signal in the cab, so that the succeeding train may pass any station at the rear end of any block on which there is no train, but is warned against passing into a block where there is already a train. By mechanism hereinafter described, the breaking of the circuit at the points 8, 9, also actuates a danger signal in the cab 95 of the succeeding train.

The circuit in the cab is illustrated dia- 100 grammatically in Fig. 2. Referring to said figure, 21 indicates a contact shoe, which is carried by a hanger 22 loosely supported at its other end from the truck frame and nor- 105

110

mally depressed by a spring 23, compressed between said hanger and a plate 24 attached to the truck frame, shown at 25. Said contact shoe is adapted to contact with any one of the contact rails 2, 3, 4, and 5, the rail 2 being shown in Fig. 2. These rails are of the usual construction, in that they are beveled at the end at which the shoe first makes contact. From said shoe a wire 26 leads to a solenoid 27, then by a wire 28 to a generator 29, and then by a wire 30 to a contact point 31 which is adapted to be closed by a contact arm 32 extending upward from the hanger 22, from which 10 arm 32 leads a wire 33 through a resistance 34, and then to the contact shoe 21. When the contact shoe arrives at the contact rail, the shoe is raised and thereby breaks the circuit between the contacts 31, 32. The 15 breaking of this circuit, if the outside circuit is not closed, deenergizes the solenoid 27, and thereby releases the core 36 thereof, which thereupon drops and strikes a bell 37, or in some other way, either directly 20 by a danger signal or indirectly by the closure of a local cab alarm circuit, as is common in the art, apprises the driver that the track is not clear. But if the core 10 at the station at which the engineer arrives has 25 been retracted by the rear solenoid 12 thereat, so that the contact is closed between the points 8, 9, then the solenoid 27 is still energized, the circuit therethrough being closed as follows:—from the generator 29 30 by the wire 28 through the solenoid 27, and wire 26 to the contact shoe 21, contact rail 2 or 3, as the case may be, wire 7, contacts 8, 9, wire 13 to ground at 15, then from the ground through the axle of the engine 35 and by a wire 39 to the other pole of the generator 29. And clearly this circuit through the solenoid 27 and through the ground is not closed unless the contacts 8, 9, are closed by the core 10 having been retracted by the passage of a train sufficiently far ahead.

The circuit which is closed by the passage of the train past the contact rail 4 is the same in the cab as that closed by the passage over the rails 2 and 3, namely from the shoe 21, wire 26, solenoid 27, wire 28, generator 29 and wire 30 to ground. On the outside it follows to the ground 15 at a station one block in the rear, and thence 40 by the wire 14 through the rear solenoid 12 of the rear station, then returning by the line wire 18 in the manner already explained. The closing of this circuit retracts the core toward the rear solenoid and closes the contacts 8, 9, so that the clear signal 45 may be given to succeeding trains. At the same time the passage of rail 4 gives the danger signal to the engineer, whenever for any reason, the above circuit is imperfect or broken, for then no current, or an in-

sufficient current, passes through the circuit and the core of the solenoid 27 drops, giving the danger signal.

While the clear signal given on passing the rail 4 apprises the engine-driver that the above described circuit to the rear station is closed, it might happen for some reason or other that, although said circuit is closed, the current therethrough is not sufficient to energize the front solenoid at the station just passed to separate the contacts 8, 9, at such station, and set the danger signal. I therefore provide means whereby the engineer may be absolutely sure that said core has been properly moved and the contacts 8, 9, separated. This is effected by means of a contact point 40 which, when the circuit is broken at the points 8, 9, is adapted to contact with the contact changer 9, the circuit then being as follows:—from the shoe 21 through the contact rail 5, wire 41, contact point 40, contact changer 9 to ground at 15, and from the ground by wire 39 through the generator 29, wire 28, solenoid 27, wire 26 to the contact shoe 21, as before, maintaining the cab signal at clear. But if the changer 9 has not been moved to break contact with the point 8 then a danger signal is given by the dropping of the core of the solenoid 27. 95

Means are provided for indicating whenever the circuit in the cab is defective or the line circuit is defective. For this purpose the wires 7 and 14 are connected by a wire 44 having therein a resistance 45, wire 44 connecting with wire 14 through a portion of wire 13. Under normal conditions when the contacts 8, 9, are separated the circuit between the wires 7 and 9 is not entirely broken but said circuit is closed through the resistance 45. Consequently a small current can pass through the circuit in the cab, although the solenoid therein is not energized sufficiently to hold up the core, which consequently drops and gives the danger signal. This current, however, while insufficient to hold up the core, is still sufficient to hold down an armature 46, and thus maintain broken a local circuit 47 having therein an alarm 48. But if the circuit is broken, either in the cab or on the line, and absolutely no current passes, then the armature 46 is released and the local circuit 47 is closed which apprises the engineer that there is a defect in the circuit. 115 120

In Figs. 3 and 4, is illustrated the construction of the solenoids used on the track. 50 indicates a casing having a cover 51, and separated by transverse partitions 52 into two chambers for the two coils 53, 54, of the solenoids. The interiors of said coils form a guideway for a core 55, upon the end of which is secured a brass extension 56 which carries an arm 57 to the upper end of which is attached a contact maker 58. Said con- 125 130

tact maker is formed with beveled edges 59, which in one of its positions are adapted to enter between two pairs of spring contact clips 60, 61, which are connected with the 5 wires 7 and 13. The high resistance wire 45 represented diagrammatically in Fig. 1 is now shown in its proper position connecting the two binding posts 62 of the two spring contact clips. Located upon the top of the 10 box at the other end of the movement of its arm are the spring contact clips 63, 64, which are connected the one with the wire 7 and the other with the wire 41 as illustrated diagrammatically in Fig. 1. These contact 15 clips are also connected by a high resistance wire 65.

In order to prevent the core and other parts from deteriorating under exposure to the weather the whole box containing these 20 parts is filled with oil. The resistance of the coils will be sufficient to maintain the oil sufficiently warm and fluid in cold weather. 66 indicates the binding posts for the two coils.

25 The advantages of the above construction are that the contacts are wiping contacts, which are self-cleaning; that the core when once moved is mechanically held in its position to which it is so moved until it is again 30 moved by the energization of a coil; and that the mechanism is compact and requires no attention, which is a particular advantage on account of these devices being generally located at great distances from a central station. However, it can be seen that 35 access can readily be had for the purpose of inspection and repairs.

I claim:—

1. In combination with a train having a 40 normally closed circuit which includes an electromagnetic device provided with two separate and independently movable masses of magnetic material, one of said masses adapted to be held in attracted position except when the device is wholly deenergized, and the other of said masses being adapted to be held in position only by the action of a stronger magnetic field through said device than that needed to hold said first mentioned 45 mass in attracted position, means for giving a special alarm when said first mentioned mass is released, said other mass serving as part of a signal, means in the path of the train at given points for breaking said normally closed circuit and establishing a separate path to complete said circuit in case of safety conditions, and means for inserting an extra resistance in said circuit in case of danger conditions.

60 2. In combination with a train having a normally closed circuit, means actuated by the passage of the train past a given point for establishing a separate path to complete said circuit in case of safety conditions, said 65 means including a solenoid having a double

coil and a core operating in both coils and having a circuit controlling element, means for inserting resistance in said path in case of danger conditions, and means on the train in the normally closed circuit for giving a 70 special alarm indication on the train in case said path is wholly interrupted.

3. In combination with a train having a relay, an armature for said relay, adapted to be held attracted except when said relay is 75 wholly deenergized, means for giving a special alarm when said armature is released, a normally closed circuit on the train including said relay, means in the path of the train for establishing a separate path to 80 complete said circuit in case of safety conditions, means for breaking the circuit through said path, and means including an extra resistance for establishing a third path to complete said circuit in case of longer 85 conditions.

4. Apparatus comprising track sections, a normally closed cab circuit, signaling means controlled by said circuit, and coöperating partial-circuit forming elements, some of 90 which are substantially on the track, said elements adapted to be placed in circuit with conductive parts forming said cab circuit when the latter is opened and having means to alter the amount of current flowing 95 through said cab circuit and actuate said signaling means, means for changing the relative positions of some of said elements with respect to each other for varying the circuit conditions as a whole in accordance 100 with the condition of a track section, said signaling means comprising a defective circuit indicating device, and means for certifying the setting of the danger signals for 105 succeeding trains, substantially as described.

5. Apparatus comprising track sections, a normally closed cab circuit having of necessity only a single electrical contact to be closed or opened, signaling means controlled by said circuit, and coöperating partial-circuit-forming elements, some of which are substantially on the track, said elements adapted to be placed in circuit with conductive parts forming said cab circuit when the latter is opened and having means to alter 110 the amount of current flowing through said cab circuit and actuate said signaling means, means for changing the relative positions of some of said elements with respect to each other for varying the circuit conditions as a whole in accordance with the condition of a track section, said signaling means comprising a defective circuit indicating device, and means for certifying the setting of 115 the danger signals for succeeding trains, substantially as described.

6. The combination with a train having a normally closed circuit, of means actuated by the passage of the train past a given point for establishing a separate path to 120

complete said circuit in case of safety conditions, means for diminishing the flow of current in said path by a predetermined amount in case of danger conditions, means 5 on the train controlled by said circuit for giving an alarm when said predetermined amount of current has been diminished, and means for giving a special alarm indication in case said path is wholly interrupted.

10 7. The combination with a train having a normally closed circuit, of means actuated by the passage of the train past a given point for establishing a separate path to complete said circuit in case of safety conditions, means for diminishing the flow of current in said path by a predetermined amount in case of danger conditions, a signal mechanism in said circuit that is actuated when the current is diminished, and 15 means including an independent circuit for giving a special alarm indication in case said path is wholly interrupted.

8. The combination with a train having a normally closed circuit of a track having

block stations, circuit making and breaking 25 appliances actuated by the passage of the train past a given point for establishing a separate path to complete said normally closed circuit in case of safety conditions, and means for diminishing the flow of current in said path by a predetermined amount in case of danger conditions, said last mentioned means comprising a series of pairs of magnets, each pair of said series corresponding to each station, separate circuits 35 for energizing the magnets at each station, said circuits each including one of the said magnets and a magnet at an adjacent station, and means mounted on the train for giving a special alarm in case the path 40 aforesaid is wholly interrupted.

In testimony whereof I have hereunto set my hand in the presence of two subscribing witnesses.

PAUL J. SIMMEN.
